(57) **CLAIM**

The ornamental design for a surface configuration of a vehicle spoiler, as shown and described.

DESCRIPTION

This application is related to the following co-pending application, of the inventor, filed on even date herewith: Application Ser. No. 29/222,963, entitled “Surface Configuration of a Vehicle, Toy, and/or Other Replicas”.

FIG. 1 is a left, rear perspective view of a surface configuration of a vehicle spoiler according to my novel design, the right, rear perspective view being mirror symmetrical;

FIG. 2 is a left, side perspective view of the surface configuration of a vehicle spoiler according to my novel design, the right, side perspective view being mirror symmetrical; and,

FIG. 3 is a left side view of the surface configuration of a vehicle spoiler according to my novel design, the right side view being mirror symmetrical.

1 Claim, 1 Drawing Sheet

FIG. 3
